WILLIAM STABLEFORD, OF LONDON, ENGLAND, ASSIGNOR TO THE ROTEX MANUFACTURING COMPANY, A CORPORATION OF NEW YORK.

MULTIPLE COPYING-MACHINE.

982,543.

Specification of Letters Patent. Patented Jan. 24, 1911.

Application filed November 11, 1909. Serial No. 527,496.

To all whom it may concern:

Be it known that I, WILLIAM STABLEFORD, of 57 Holborn Viaduct, in the city of London, England, merchant, a subject of the 5 King of Great Britain, have invented certain new and useful Improvements Relating to Multiple Copying-Machines, of which the following is a specification.

My invention relates to improvements in 10 multiple copying machines and more particularly to the machine described in my specification Serial No. 515450, and it has for its object improved means for supporting and applying tension or drag to the roll 15 of paper and to accommodate the various widths of paper, improved means for feeding the letters (or other documents to be copied) to the copying rollers, and improved means for actuating the paper cutting 20 mechanism whereby the paper may be severed in similar lengths, or in any suitable dissimilar lengths, and with rectangular cut edges.

In the accompanying drawings, Figure 1 25 is a general side view of the improved copying machine. Fig. 2. is a detached view of the letter feeding mechanism. Fig. 3. is a detached side view and Fig. 4. is a front view partly in section of the apparatus for 30 actuating the paper cutting mechanism. Fig. 5. is a vertical section illustrating the paper cutting mechanism. Fig. 6 is a front view of the paper draw roller or cylinder and guard which feeds and guides the paper 35 to the cutting mechanism. Fig. 7 is a sectional view illustrating one of the paper roll supporting pins.

Referring to Figs. 1 and 2, the damped paper *a* passes upward from the damping appliance *b* over an elevated roller *c* and downward to the copying rollers *d* *d'*. The roller *c* is carried in a frame or frames *e* which is or are pivoted at *c'* to the main frame *f*, said frame *e* being movable from 45 the copying rollers by swinging the same upon its pivots *e'* in order to facilitate the threading of the paper between the copying rollers *d* *d'* when a new roll of paper has been fitted. The roller *c* is located above 50 the level of the copying roller *d'* so as to provide a bight of the paper *a* on the roller *d'* in a convenient position to receive the letter, or other document to be copied, between the paper and the roller *d'*. Attached to the two ends of the copying roller

d, or fixed upon its shaft *d*², are two cams *g* and *h*. The cam *g* is designed to permit a feed pressure roller *i* to be pressed upon the roller *d'* and grip the letter which has previously been placed in position by hand upon the table *i'*. The roller *i* is carried in a frame *g'* pivoted at *g*² and is rocked in one direction by the cam *g* by means of the arm *g*³ and anti-friction wheel *g*⁴, and in the opposite direction by the spring *g*⁵. The cam *h* is designed to actuate a swinging frame *h'* in order to bring a number of fingers *h*² fixed thereto into position, and this is effected by means of a pair of arms *h*³ fixed to a rock shaft *h*⁴ and connected by 60 links *h*⁵ to the frame *h'* which is pivoted at *h*⁶, one of said arms *h*³ being fitted with an anti-friction wheel *h*⁷ running on the cam *h* and a spring *h*⁸ to effect the return motion. The frame *g'* is also provided with fingers 65 *g*⁶ which interlace with the fingers *h*² and thus form at their intersecting point a stop for the letter which is laid upon the table *i*, with its forward edge in contact with the interlacing fingers. Upon the machine being 70 set in motion the fingers *h*² swing away and permit the letter to drop on to the roller *d'*; the pressure roller *i* then descends and presses the letter on to the roller *d'* and simultaneously the fingers *g*⁶ guide the forward end of the letter downwardly between the damped paper *a* and the roller *d'* so that it becomes drawn in with the paper between the rollers *d* *d'*. In the meantime the frames *g'* and *h'* have swung back to their 75 initial positions ready for the next letter which is placed in position but which cannot be fed between the rollers *d* *d'* owing to the fingers *h*² separating the moving letter from the one just laid on the table. The 80 cams *g* and *h* are arranged so that they allow their respective mechanisms to come into action at the proper time to insure the correct distance from one letter to the other 85 as copied on the paper *a*.

The paper cutting mechanism hereinafter described may be actuated automatically, during the rotation of the copying rollers *d* *d'* by the usual crank handle *f'* through spur gearing (Fig. 1) or it may be disconnected and actuated by hand. For this purpose I provide a rock shaft *h* (Figs. 3 and 4) which extends across the machine and is carried in suitable bearings, one end of this shaft having fixed thereon an arm 90

100

105

110

115

2
k' provided with a wheel *k*² which runs in a cam groove *k*³ formed in the inner face of the driving wheel *l* which is fixed on the shaft *d*² of the copying roller *d*. The other end of the shaft *k* has fixed thereto an arm 5 *k*⁴ formed as a quadrant plate with a hole or notch *k*⁵ therein, and also carries loosely thereon a lever *m*, the upper end of which is formed as a handle *m'* and the lower end of which is connected by a link *m*² to the 10 sliding cutter frame. The lever *m* is provided with a suitable bolt *m*³, or similar locking device, which may be caused to engage with the hole or notch *k*⁵ in the quadrant plate *k*⁴ when it is desired to lock the 15 two together and actuate the paper cutting mechanism automatically at predetermined intervals, so as to sever the paper into similar predetermined lengths. By withdrawing the locking device *m*³, the paper cutting 20 mechanism may be actuated by hand by means of the handle *m'* when dissimilar lengths of paper are to be secured. Preferably, the cam *k*³ the spur wheel *l* and the 25 grooved wheel *l'* are formed integral as shown in Fig. 4. The grooved wheel *l'* serves for rotating the draw roller herein-after described by means of a belt or band *l*² as indicated by dotted lines in Fig. 1. 30 Referring to Figs. 5 and 6 the draw roller is formed of a number of velvet covered drums or cylinders *n* fixed to a common spindle *n*', the spaces between the drums or cylinders accommodating fingers *n*² formed 35 on the guard plate *n*³ which prevent the damp paper *a* passing too far around the draw roller before becoming detached. The jockey or idle roller which rests against the 40 velvet roller is preferably formed with a number of toothed, ribbed, or milled cylindrical surfaces *o* in order to insure its rotation in contact with the damp paper and prevent the adherence of the paper to the 45 jockey roller. 50 The damp paper *a* passes to the draw roller over a bar or roller *p* which causes the letter to become detached and pass onward down the letter tray *p'* which is detachably fitted to the main frame *f*, the 55 paper *a* passing downward between the two cutters of the paper cutting mechanism. This mechanism comprises a pivoted cutter frame *a*, carrying a cutting blade and supporting the guard plate *n*³, and a sliding cutter frame *s'* to which the operating link *m*² is pivoted as shown in Fig. 1, the cutter frame *s'* being provided with a cutting blade and being mounted in suitable guides 60 *s*³ *s*⁴. Owing to the continued progress of 65 the paper however, the cut across the paper is more or less oblique instead of being at a right angle to the side edges. This defect I overcome by utilizing the back guard *r* as a clamp to hold the paper during the 70 cutting operation. For this purpose, the

guard, which is pivoted at *r'* is provided with a pin *r*² pivoted thereto and passing through a bracket *r*³ attached to the sliding cutter frame *s'*; a spring *r*⁴ is interposed between the bracket and the guard *r* and a 75 nut *r*⁵ is fitted to the end of the pin. It will thus be seen that the first part of the movement of the cutter frame *s'* is imparted to the guard *r* through the spring *r*⁴ pressing and clamping the paper *a* against the pivoted cutter frame *s* (or against the lower end of the guard plate *n*³), the spring allowing the full movement of the cutter frame *s'* to be effected. In the meantime the paper has accumulated between the 80 guards *n*³ and *r* as shown by the dotted curved line, but when the sliding frame *s'* has nearly returned to its original position the guard *r* returns from the clamping position and allows the accumulated paper to 85 fall through between the two cutters.

For collecting the severed portions of paper strip as they fall from the cutting mechanism a collecting bar *t* is fixed to the sliding cutter frame *s'* as described in my 90 before mentioned specification. On operating the cutting mechanism the paper *a* is pressed against the side of the bar *t* by a frame *u* pivotally mounted in connection with the side arms *v* which are operated by 95 the cutting mechanism by contact with the sliding cutter frame *s'* (see Fig. 1), a spring *u*' being employed to control the motion of the frame *u*. A depending plate *w* is fixed to the arm *v* and serves at the 100 moment of severing, to throw the upper part of the paper over the bar *t* so that it becomes suspended thereby.

In order to provide for the various widths of paper which may be used and to insure 105 equal tension or drag for all widths, one or both of the supporting pins *x* (Fig. 7) is or are formed with grooves *x*' at distances apart corresponding to the various widths of paper 110 commonly used, and the pins are fixed after adjustment in their supporting sockets by binding or set screws *x*² which enter said grooves. The inner end of each pin is reduced in diameter and there carries a rotary head *y* formed with studs *y*' *y*², or other devices to engage the roller *z* which carries the roll of paper *z*', a dished or like spring metal plate *y*³ being interposed between the head *y* and the shoulder on the pin formed by the said reduced part, to provide the 115 necessary resistance to the rotation of the head and thereby apply the drag to the roll of paper as it unwinds.

I claim:—

1. In a multiple copying machine, the 125 combination of a paper damping device, a pair of copying rollers, an elevated roller over which the damped paper passes downward to said copying rollers, a feed pressure roller, operating means for said feed 130

pressure roller, supporting fingers for the forward end of the letter, operating means for said supporting fingers, and downwardly projecting guides for the forward 5 end of the letter, as set forth.

2. In a multiple copying machine, the combination with a paper damping device, a pair of copying rollers and an adjustable pressure roller, of an elevated roller, an adjustable 10 supporting frame for said elevated roller, a feed pressure roller, a frame carrying said feed pressure roller, actuating means for said frame, downwardly projecting guides on said frame, supporting fingers for the letter, a frame carrying said supporting fingers, and actuating means for the finger frame, as set forth.

3. In a multiple copying machine, the combination with a paper damping device 20 and a pair of copying rollers, of an elevated roller, an adjustable supporting frame for said roller, a feed pressure roller, a pivoted frame carrying said feed pressure roller, downwardly projecting fingers on said frame, letter supporting fingers interlacing with the fingers first named, a pivoted frame carrying said supporting fingers, and cams rotated with the main copying roller adapted to actuate the feed roller frame and the supporting 25 fingers frame, as set forth.

4. In a multiple copying machine, a letter feeding device comprising an elevated roller from which the dampened paper passes downward to the copying rollers, a feed pressure roller carried by a pivoted frame, downwardly projecting fingers on said frame, letter supporting fingers interlacing with the fingers first named, the downwardly projecting fingers guiding the letter between the dampened paper and the copying rollers, a pivoted frame carrying said supporting fingers, and cams rotatively connected with the main copying roller to actuate the pivoted frames at the proper time, as set 45 forth.

5. In a multiple copying machine, the combination with a paper damping device and a pair of copying rollers, of a letter supporting device, a letter feed roller, a letter guiding device, a paper cutting mechanism, an automatic operating train for said paper cutting mechanism and including an element which may be operated by hand, and a disconnecting device to dissociate the 50 hand operated element from the driving elements of said train whereby the paper cutting mechanism may be operated by hand, as set forth.

6. In a multiple copying machine, an alternative operating device for the paper cutting mechanism, comprising a rock shaft mounted in the main frame, an arm fixed on said rock shaft, a cam rotatively connected with the main copying roller and operating 60 said arm, a quadrant arm fixed on said

rock shaft, a lever loosely mounted on said rock shaft, means connecting the lower end of said lever to the paper cutting mechanism, a handle on the upper end of said lever, and an interlocking device connecting said lever with said quadrant arm, as set forth. 70

7. The combination with a multiple copying machine having a paper damping device and a pair of copying rollers, of a supporting pin for the roll of paper formed with annular grooves at a distance apart corresponding to the various widths of paper used, a socket or bearing for said pin, and fixing means in said socket or bearing engaging in any one of said grooves, as set 75 forth.

8. The combination with a multiple copying machine having a paper damping device and a pair of copying rollers, of a supporting pin for the roll of paper formed with annular grooves, a bearing for said pin, fixing means for said pin, a rotary head on said pin adapted to engage the roll of paper, and a resilient retarding device interposed between said rotary head and said 80 pin, as set forth.

9. In a multiple copying machine having a paper damping device and a pair of copying rollers, a draw roller composed of a number of velvet covered drums or cylinders fixed to a common spindle, a jockey or idle roller formed with a longitudinal ribbed periphery, and a guard plate formed with fingers projecting into the spaces between said drums or cylinders, as set forth. 95

10. In a multiple copying machine having a paper damping device, a pair of copying rollers, and a paper cutting mechanism, the combination of a draw roller composed of a number of drums or cylinders, an idle ribbed roller, a guard plate formed with fingers projecting between said drums or cylinders, and a clamping device for the paper operated by the moving portion of the paper cutting mechanism as set forth. 100

11. In a multiple copying machine having a paper damping device, a pair of copying rollers, a guard plate and a paper cutting mechanism, a paper clamping device comprising a pivoted back guard, and a resilient 115 connection with the moving part of the paper cutting mechanism adapted to press said back guard against said guard plate, as set forth.

12. In a machine of the type set forth, a roller for supporting a paper roll, a supporting pin for the roller, a head provided on the pin for engagement with the roller to cause the pin to turn therewith, and a resilient retarding device interposed between 125 said rotary head and a shoulder of the pin.

13. In a machine of the type set forth, a roller for supporting a paper roll, a supporting pin for the roller, a head provided on the pin for engagement with the roller to 130

cause the pin to turn therewith and a resilient retarding device for engagement with said head.

14. In a multiple copying machine, the combination with copying rollers, means for feeding a dampened sheet between the copying rollers, and a letter table, of an intermittent feed device for transferring the letters singly and successively from the table to a position between one of the copying rollers and the dampened sheet, said device comprising two series of interlacing fingers, movable into and out of interlacing relation, said fingers in interlacing relation serving as a stop to support the letter passing between the dampened sheet and the said feed roller from the adjacent letter on the table, and one series of said fingers serving as a movable guide to deflect a letter between said dampened sheet and said feed roller.

15. In a machine of the type set forth, the combination with copying rollers, means for feeding a dampened sheet between the copying rollers, and a letter table, of a letter feed roller bodily movable to effect the transfer of a letter to one of the copying rollers, and guide fingers bodily movable coextensively with the letter feed roller to deflect the letter transferred by the feed roller between the said copying roller and the dampened sheet.

16. In a multiple copying machine, the combination with a pair of copying rollers, of means for feeding a dampened sheet between the copying rollers and including a frame pivoted adjacent the copying rollers and provided with a roller over which the dampened sheet passes, said last named roller being so positioned as to form a bight in the dampened sheet before its passage through the copying rollers.

17. In a multiple copying machine, copying rollers, means for feeding a dampened sheet continuously between the copying rollers, a sheet cutting device, means for intermittently operating the sheet cutting device, and means for temporarily and intermittently clamping the paper in advance of the sheet cutting device and during the sheet cutting operations.

18. In a multiple copying machine, the combination with a pair of copying rollers and a paper cutting mechanism, of a draw roller interposed between the copying rollers and the cutting mechanism and comprising spaced paper engaging drums, and a guard plate disposed under the draw roller and provided with fingers which project into the spaces between the drums.

19. In a multiple copying machine, the combination with copying rollers, sheet cutting mechanism and a draw roller interposed between the copying rollers and the sheet cutting mechanism, of a sheet clamping mechanism interposed between the draw roller and the sheet cutting mechanism.

20. In a multiple copying machine, the combination with a draw roller and sheet cutting mechanism, of means for intermittently operating the sheet cutting mechanism, a paper clamping mechanism interposed between the draw roller and the sheet cutting mechanism, and means for intermittently operating the paper clamping mechanism.

21. In a multiple copying machine, the combination with a draw roller and sheet cutting mechanism including a movable blade of a stationary guard plate interposed between the draw roller and the sheet cutting mechanism, and a clamping plate associated with the movable blade for movement therewith and coöperating with the guard plate to clamp the sheet of paper fed over the draw roller during the sheet cutting operation.

22. In a multiple copying machine, the combination with a draw roller and sheet cutting mechanism including a movable blade, of a stationary guard plate interposed between the draw roller and the sheet cutting mechanism, a clamping plate for co-operation with the guard plate to clamp the sheet fed over the draw roller during the sheet cutting operation, and resilient connections between the movable blade and the clamping plate to cause the movement of the latter with the former.

23. In a multiple copying machine, the combination with a pair of copying rollers, means for feeding a dampened sheet therebetween, and a letter table, of means for deflecting a letter transferred from the letter table between said dampened sheet and one of the copying rollers, and means movable relatively to said deflecting means and intermittently coöperating therewith as a stop to separate the letter passing between said dampened sheet and said copying roller from the adjacent letter on said table.

In testimony whereof I have hereunto set my hand in presence of two subscribing witnesses.

WILLIAM STABLEFORD.
